FIG. I.

FIG. 2.

FIG. 3

INVENTOR
Robert Cooper,
by James L. Morris,
Attorney.

UNITED STATES PATENT OFFICE.

ROBERT COOPER, OF LONDON, ENGLAND.

DEVICE FOR USE IN DISINFECTING TELEPHONE INSTRUMENTS.

1,381,081.

Specification of Letters Patent. Patented June 7, 1921.

Application filed November 16, 1920. Serial No. 424,410.

To all whom it may concern:

Be it known that I, ROBERT COOPER, a subject of the King of Great Britain, residing at London, England, have invented 5 a new and useful Improved Device for Use in Disinfecting Telephone Instruments, of which the following is a specification.

This invention relates to an improved device for use in disinfecting telephone instruments, more especially the mouthpieces of 10 telephonic transmitters.

Disinfecting devices for telephone mouth pieces and the like have already been suggested wherein there is applied between the 15 ordinary mouth-piece and the diaphragm of a telephone transmitter a tube having radial perforations. One end of this tube is formed with internal screw threads which fit over the screw threads of the mouth piece, 20 while the other end of the tube has external screw threads adapted to fit into a socket in the casing of the diaphragm. Around this perforated tube there is fitted a removable box that contains cotton wool or other 25 porous material saturated with liquid anti-septic and is made in two parts which are fitted together and have a central hole in each face to receive the perforated tube.

According to my invention, the cotton 30 wool or like absorbent material forming the annular pad is arranged in the annular space between retaining cylinders of perforated sheet metal, wire gauze or the like, arranged one within the other whereby the 35 absorbent material is securely retained in position and the pad can be readily removed and replaced in the casing. The casing for receiving the annular pad is provided with suitable supporting surfaces for the pad 40 and may or may not be provided with an internal perforated tube. It preferably has a male thread on one side to engage with the socket in the telephone casing and a female thread on the other side to receive 45 the male thread on the mouthpiece.

In the accompanying drawing I have shown how my said invention may be conveniently and advantageously carried into practice. In this drawing:—

50 Fig. 1 is a front elevation of a disinfecting device constructed according to my invention, and

Fig. 2 a rear elevation thereof, the mouth-piece and transmitter being removed.

55 Fig. 3 is a longitudinal central section of the device with a mouthpiece fitted thereto.

A is a tube, preferably of metal, provided with lateral perforations B, B and with a male screw-thread C at one end to screw into the transmitter casing. At its other end it 60 has a screw threaded socket D to receive a nipple E, on to which is screwed the mouth-piece F. The tube A also has near its front end a flange A' against which rests an annular disk G provided at its periphery 65 with a cylindrical internally screw-threaded socket H to receive the screw-threaded end of a cylindrical casing J having an integral rear wall K shaped to fit against the exterior of a telephone transmitter and adapted to abut against a flange L on the rear part 70 of the tube A.

In the annular space in the casing J, K there is arranged a pad M of cotton wool enclosed between cylinders N, O of perforated 75 sheet metal.

In order to permit the introduction of a fresh supply of volatile disinfectant, the box may be opened and the pad removed and reimpregnated, or if desired replaced by a 80 fresh one.

It is obvious that the box or annular casing for the disinfectant may be constructed and arranged in any other suitable manner. It may moreover be applied to the ear pieces 85 of receivers in an analogous manner.

What I claim is:—

1. A device for disinfecting telephones, comprising an annular casing formed of separable members, an annular absorbent 90 pad in said casing, said pad comprising concentric perforated tubes having absorbent material in the annular space between them, means for supporting said pad concentrically in said casing, and means for securing 95 the device to a mouthpiece and to a telephone instrument.

2. A device for disinfecting telephones, comprising an annular casing formed of separable members, an annular pad in said casing comprising concentric perforated tubes having absorbent material in the annular space between them, a perforated tube in said casing co-axial with said pad and having means for securing it to a mouthpiece 100 and to a telephone instrument, said tube being provided with flanges to support said pad and to abut against the inner faces of said separable members.

3. A device for disinfecting telephones, 110 comprising an annular casing formed of separable members, provided with complemen-

tal screw-threads for securing said casing-members together, an annular pad comprising concentric perforated tubes having absorbent material in the annular space between them, an axial perforated tube in said casing and provided with means for securing its opposite ends to a mouth-piece and to a telephone instrument, respectively, said tube

having flanges on its periphery adapted to support said annular pad and to abut against 10 the inner faces of the separable members of the annular casing.

ROBERT COOPER.
